UNITED STATES PATENT OFFICE.

JOHN N. POMEROY, OF PHILADELPHIA, PENNSYLVANIA, ASSIGNOR TO GENERAL DIE-CASTING COMPANY, OF READING, PENNSYLVANIA, A CORPORATION OF PENNSYLVANIA.

DESIGN FOR AN AUTOMOBILE RADIATOR-CAP ORNAMENT.

Application filed June 29, 1927. Serial No. 22,605. Term of patent 3½ years.

To all whom it may concern:

Be it known that I, JOHN N. POMEROY, a citizen of the United States, residing at Philadelphia, county of Philadelphia, State of Pennsylvania, have invented a new, original, and ornamental Design for Automobile Radiator-Cap Ornament, of which the following is a specification, reference being had to the accompanying drawing, forming a part thereof.

Figure 1 is a side elevation of the automobile radiator cap ornament,

Figure 2 is a plan view of the same, and,

Figure 3 is a front end elevation of the same.

I claim:—

The ornamental design for an automobile radiator cap ornament, as shown.

JOHN N. POMEROY.
